UNITED STATES PATENT OFFICE.

JOHN H. BICKFORD, OF SALEM, MASSACHUSETTS, ASSIGNOR OF ONE-THIRD
TO S. FRED SMITH, OF SAME PLACE.

SIGNALING APPARATUS FOR RAILWAY-TRAINS.

SPECIFICATION forming part of Letters Patent No. 355,055, dated December 28, 1886.

Application filed February 15, 1886. Serial No. 191,910. (No model.)

To all whom it may concern:

Be it known that I, JOHN H. BICKFORD, of Salem, county of Essex, and State of Massachusetts, have invented an Improvement in 5 Signaling Apparatus for Railway-Trains, of which the following description, in connection with the accompanying drawings, is a specification, like letters on the drawings representing like parts.

10 This invention has for its object to provide a train of cars with signaling apparatus, whereby the engineer may be notified when to start or stop the train; also to provide a moving train with suitable mechanism whereby a 15 bell located at a crossing or at a station may be rung, to thereby indicate the approach of the train.

In accordance with this invention a magneto-generator is located within the engine-cab and 20 operated preferably by an independent motor, and an open circuit leading from the generator extends through the train, suitable circuit-closers being located along the line, which, when operated, cause a magneto-bell located 25 within the engine-cab to vibrate. The electric wires forming the circuit are coupled together between the cars by a coupling so constructed that when in engagement an open circuit is insured, and when pulled apart, as 30 in case of accident or otherwise, the circuit automatically closes, thus giving warning to the engineer of such an event. Suitable means are also provided by which the coupling when disengaged may be normally kept in such condition as to insure an open circuit.

35 A contact-roller carried upon any of the trucks of the train—as, for instance, the tender—is connected in circuit with the said generator, and is arranged to make contact at intervals with 40 an independent rail when nearing a crossing or station, said rail being connected by an electric wire or conductor with a magneto-bell located at the crossing or station, so that when the train nears the crossing or station the 45 magneto-bell at the said crossing or station is caused to vibrate.

Figure 1 shows in side view a portion of a train of cars provided with signaling apparatus embodying my invention; Fig. 2, a lon-

50 gitudinal section of the coupling connecting the electric wire between the cars. Fig. 3 is a detail of the contact-rail; Fig. 4, a perspective view of a portion of the track, showing the independent contact-rail and the magneto-bell as adjacent thereto; Fig. 5, a section of a circuit-closer depending from the electric conductor within the cars, and Fig. 6 a detail of a driving-coupler to insure an open circuit upon the train.

The engine A, the cab and rear end portion 60 of which is shown in Fig. 1, carries any suitable magneto-generator, A', the armature-shaft of which is rotated by a motor, herein shown as a small engine, A''. An open circuit, formed by the wires 2 3, leads from the generator A', located in the cab, and through the train, one car, B, of which is shown on the drawings.

Suitable circuit-closers (herein shown as ordinary press-buttons, a) are interposed along 70 the line at any desirable point, inside or outside the car, but herein shown as within the car, and when depressed by the conductor or other person the circuit 2 3 is closed, causing a magneto-bell, b, located within the engine-cab to vibrate. Code-signals representing a 75 definite number of times that the circuit is closed by the circuit-closer a, and known to the engineer, notify him to start or stop the train.

The coupling to be herein described for connecting the electric wires of several cars with each other, or with the engine, (see enlarged detail, Fig. 2,) consists of two blocks, c c', of similar dimensions, and each connected with the 85 wires to be connected together. The coupling-block c is provided with a pair of springs, c² c³, fitted into a socket, c⁴, made in abutting faces of the coupling-block, the free ends of the said springs normally remaining in contact 90 with each other. Beside the socket c⁴, containing the springs, a plug, c⁵, is inserted, the end of which projects beyond the abutting face of the block c, consisting of the insulated portion c⁶ and the conducting portion c⁷.

The coupling-block c' is constructed just the reverse of the coupling-block c, so that the projecting portion of the plug c⁵ enters a socket,

c^8 , between the springs c^9 c^{10} of the coupling-block c' , and the projecting portion of the plug c^{12} enters the socket c^4 , and between the springs c^2 c^3 of the coupling-block c . Thus when the 5 two coupling-blocks are engaged the springs c^2 c^3 and c^9 c^{10} of each coupling-block will be disengaged.

The wires 2 3 pass longitudinally through the coupling-block, the wire 2 connecting the 10 plug c^{12} and spring c^9 , while the wire 3 is connected with the spring c^{10} , and, as will be seen, when the coupling-blocks are disengaged, as in Fig. 2, a closed circuit is formed by the springs c^9 c^{10} coming in contact with each other; 15 but when brought into engagement with each other and the springs separated, as described, a normally-open circuit is formed, as follows: the wire 3, spring 10, conducting portions c^7 of the plug c^5 , from which latter the wire 3 20 continues, and with the wire 2 a similar connection is made.

To retain the coupling-blocks c c' in engagement, spring-latches c^{15} c^{16} are secured, respectively, to each coupling-block, which co-operate with annular flanges c^{17} c^{18} of the coupling-blocks. 25

If the coupling-blocks c c' are accidentally or otherwise disengaged, as in the case of a car parting from the train, the circuit is automatically closed, and consequently warning 30 given to the engineer of such an event. To insure an open circuit with the end coupling-piece upon the last car, a dummy-block, d , (see details, Fig. 6,) is provided. The dummy-block d , preferably suspended from each 35 end of a car to be engaged with the coupling-block to insure an open circuit, consists, essentially, of features shown in either coupling-block, Fig. 2, with the exception that the 40 wires are omitted.

When it is desired to stop a train, the circuit may be closed by the circuit-closers a one, two, or more times, thus causing the magneto-bell b to respond a similar number of times, 45 and to start a train a different signal similarly operated may be employed. As shown in this instance, the wires pass through the cars, similar to the bell-cord commonly employed, and, if desired, a circuit-closer, as 50 shown in section, Fig. 5, may be suspended from the wires. This circuit-closer consists of a tassel, e , suspended from the main wire by the wires 4 5; or it may be suspended by a cord inclosing the said wires 4 5. A press-button 55 of ordinary construction is located within the tassel, so that the same is concealed from view, but within ready reach of any person knowing its place of concealment. Branch wires 6 7 are connected with the wires 2 3, the wire 6 6c being connected with one of the wheels of the truck, and thereby grounded, while the wire 7 is connected with a frame, f , attached to the under side of the truck-frame C of the tender of the engine, the said frame f carrying a fork, 65 f' , the shank f^2 of which is encircled by a spiral spring controlling the rising and falling

movement of said fork, a contact-roller, f^3 , rotated upon a shaft, f^4 , having its bearings in the arms of the fork f' .

Suitable springs, f^5 , are interposed between 70 the arms of the fork and the roller, that the latter may yield laterally, while the spring f^2 permits the same to yield vertically. The contact-roller f^3 is adjusted to make contact with an independent rail, m , located between the 75 ordinary rails, m^1 m^2 , of the track. The rails m are placed at any desired distance from the crossing or station, and are connected by wire 8 with a magneto-bell, m^3 , which is located at the crossing or station, the said magneto-bell m^3 being grounded by wire 9. The rail m is of such a length as to cause the magneto-bell m^3 to respond for a limited interval of time, as desired. One of the rails, as m^2 , has a ground-wire, 10, connected therewith, so 80 that a ground-circuit is formed when the contact-roller f^3 comes in contact with the rail m .

It will be seen that as the engine nears a crossing or station, at which point a magneto-bell—as m^3 , for instance—is located, the contact-wheel f^3 comes in contact with the rail m , and causes the bell m^3 to respond, notifying passers-by of the approach of the train. 85

I am aware that magneto-bells have been employed as crossing or station signals, and 95 that a magneto-generator located adjacent thereto has been set in operation by a passing train; but I am not aware that a magneto-bell has been employed as a crossing or station signal and caused to vibrate by a magneto-current generated upon the train. 100

By employing the signaling apparatus herein described a single magneto-generator carried upon the engine may generate a current which may be utilized to ring the crossing and station signals, and also the magneto-bell located within the engine-cab, and thereby greatly reduce the expense of this system of signaling. 105

I claim—

1. A coupling for electric signaling apparatus for railway-trains, consisting of the blocks c and c' , each provided with a socket containing two metallic springs normally in contact with each other, and a plug having a projecting portion, partly conductive and partly non-conductive of electricity, and adapted to enter the socket of the opposite block, the circuit-wire 3, connected to the plug and one spring of one of the blocks, and the circuit-wire 2, connected to the other spring of said block, and the said wire 2 connected to the plug and one spring of the other block, and the said wire 3 connected to the other spring of said last-named block, so that when the 115 coupling-blocks are disengaged a closed circuit is formed, which is broken by the entrance of the plugs between the springs, and hooks engaging flanges to hold the blocks in engagement, substantially as described. 120

2. The combination of a magneto signal-bell and its circuit, a moving-train circuit, a 125

110

115

fixed rail, m , connected with the said bell-wires, and a contact-roller, f^3 , carried upon one of the trucks of the train and having vertical and lateral springs, to adapt it to irregularities in the road as it is in contact with the said fixed rail, substantially as shown and described.

In testimony whereof I have signed my name to this specification in the presence of two subscribing witnesses.

JOHN H. BICKFORD.
